[57] CLAIM

The ornamental design for a guitar, as shown and described.

DESCRIPTION

FIG. 1 is a top plan view of a guitar, showing my new design;

FIG. 2 is a left side elevational view thereof, the undis-

closed right side is a mirror image of that side shown;

FIG. 3 is a bottom plan view thereof; and

FIG. 4 is a front elevational view thereof.

Fig. 3

Fig. 4
